UNITED STATES PATENT OFFICE.

WILLIAM F. BOUCHÉ, OF DEPEW, NEW YORK, ASSIGNOR TO GOULD COUPLER COMPANY,
A CORPORATION OF NEW YORK.

DYNAMO SUSPENSION.

1,242,513.

Specification of Letters Patent.

Patented Oct. 9, 1917.

Application filed May 22, 1915. Serial No. 29,710.

To all whom it may concern:

Be it known that I, WILLIAM F. BOUCHÉ, a citizen of the United States, and a resident of Depew, county of Erie, and State 5 of New York, have invented certain new and useful Improvements in Dynamo Suspensions, of which the following is a specification.

My invention relates to improvements in 10 dynamo suspensions and more particularly to apparatus for supporting dynamos on car trucks, which dynamos are adapted to be driven from the car axle. One object of my invention is to provide a simple and efficient 15 arrangement, whereby the dynamo may not only be easily adjusted to tighten the driving belt thereof, but which arrangement shall also have but few parts, which are simple and easy of construction and assembly. Further objects, features and advantages will more clearly appear from the 20 detailed description given below, taken in connection with the accompanying drawings, which form a part of this specification.

25 In the drawings Figure 1 is a plan view of one embodiment of my invention applied to a car truck. Fig. 2 is a section taken on the line 2—2 of Fig. 1. Fig. 3 is a front view of the same. Fig. 4 is a side view of 30 the same. Fig. 5 is a detailed section taken on the line 5—5 of Fig. 4, illustrating the method of connecting two parts of the supporting frame.

In the drawings 1 represents the car truck, 35 2 one of the car axles and 3 the wheels thereof. Secured to the sides of the truck 1 are horizontal bars 4, one on each side of the truck, which bars project horizontally from the truck, passing through apertures 40 in the end of the truck frame. 5, 5 represent additional supporting bars, having their outer ends bolted to the bars 4 at 6, and having their ends bolted to the truck frame at 7. For a portion of their length, adjust- 45 cent their outer ends, the bars 4 and 5 of each pair run parallel to one another and on top of these parallel portions are placed supporting blocks 8. Each block 8 rests upon both the bars 4 and 5, and is apertured 50 in its center as at 9, and provided with upwardly extending ears 10 and downwardly extending ears 11, lying adjacent to the bars

4 and 5. The ears 11 are bolted to the bars 4 and 5 by means of bolts 12, which bolts pass through slots 13 in bars 4 and 5, in 55 order that blocks 8 may be adjusted for a short distance longitudinally on top of the bars 4 and 5, and secured in any desired adjusted position by means of the bolts 12. Pivotedly mounted between the ears 10, by 60 means of pivots 14, and extending downwardly through the apertures 9 are members or rods 15. Adjacent their lower ends the rods 15 are bent laterally as at 16, and connected by a cross member 17 at their lower 65 ends. The members 15, 16, 17 are preferably made of one integral rod, having an eye at the top through which the pivot 14 passes, in which member the portions 15, 16 may be considered as side arms and portion 70 17 as a cross piece connecting the lower ends of said arms, the lower portion of said member being bent backward to one side at the junction of parts 15 and 16. Also near the lower end of the members 15, at the 75 junction of the portions 15 and 16, there are provided laterally extending members or side arms 18, each clamped to one of the rods 15, where it is bent laterally adjacent its lower portion. The members 18 are 80 clamped to the members 15 and 16, by means of clamping plates 19 and bolts 20 (see Figs. 4 and 5).

Connecting the lower ends of the members 18 is a cross member 21. The members 85 18 and 21 are preferably made of one integral rod. The members or cross bars 17 and 21 are spaced apart and arranged substantially parallel to the car axle and spanned by members 22, clamped to the 90 cross pieces 18 and 21 by means of cap plates 23 and bolts 24. The members 22 are provided with upwardly extending lugs 25, through which pass rods 26, and a dynamo 27 is provided with depending lugs 28 95 (see Fig. 3), through which the rods 26 pass, whereby the dynamo is rigidly supported upon the members 22, and consequently by the cross rods or bars 17 and 21.

Bars 4 at their outer ends are bent downwardly as at 30, and each of the clamps 19 is provided with a downwardly extending ear 31, to which is pivotally attached a rod 32, which rod passes through an aperture 100

in the downwardly extending portion 30 of the bar 4 on its side of the apparatus, and encircling the outer end of each rod 32 is a tension spring 33. Screw threaded upon the outer end of each rod 32 is a hand nut 34, for the purpose of compressing the spring 33 and tending to pull the members 15 and the dynamo supporting frame outwardly and away from the car axle about 10 the pivots 14 as a center, to apply or increase the tension upon the belt 35, passing over a pulley 36 on the car axle and a pulley 37 on the dynamo, for the purpose of driving the dynamo from the car axle.

15 It will be seen that the arrangement for suspending the dynamo by a swinging structure is extremely simple, requiring but few parts, and yet the dynamo may be adjusted laterally along the bars 17 and 21, by loosening the clamping plates 23, and likewise a proper tension may be applied to the belt by operating the nuts 34 to swing the dynamo in or out, as desired. A slight adjustment may also be had of the supporting blocks 8, by means of the slots 13.

30 Although I have described my invention with respect to its preferred form, nevertheless, I do not desire to be limited to the embodiment shown and described, as many changes and modifications may be made without departing from the spirit and scope of my invention in its broader aspect.

What I claim as new and desire to secure by Letters Patent of the United States is:

35 1. A dynamo suspension having in combination with a car truck, supporting members extending from the truck, a pair of blocks carried upon said supporting members, one at each side of the suspension, a 40 supporting frame pivotally suspended from said blocks, said frame having two parts extending downwardly from said blocks respectively, two parts extending laterally from each of said downwardly extending parts, one of said lateral parts being integral with said downwardly extending parts, and two spaced apart cross members parallel with the car axle, connecting the laterally extending members on one side with the 45 laterally extending members on the other side of the suspension, and means whereby the dynamo is adjustably carried by said cross members.

50 2. A dynamo suspension having in combination with a car truck, two pairs of bars extending from the truck, one pair on each side of the truck, the bars of each pair being spaced from and running parallel to one another adjacent the outer ends thereof, a 55 pair of blocks carried upon said bars, one on each side of the truck, each block being bolted to each member of each pair of said bars, the bolts passing through slots in the bars, whereby adjustment of the blocks longitudinally of the bars is permitted, and a

swinging dynamo supporting frame pivotally supported from said blocks.

3. A dynamo suspension having in combination with a car truck two pairs of bars extending from the truck, one pair on each side of the truck, a pair of blocks carried upon said bars, one on each side of the truck, each block being bolted to each member of each pair of said bars and a swinging dynamo supporting frame pivotally supported from said blocks. 75

4. A dynamo suspension having in combination with a car truck, two pairs of bars extending from the truck, one pair on each side of the truck, the bars of each pair being spaced from and running parallel to one another adjacent the outer ends thereof, a pair of blocks carried upon said bars, one on each side of the truck, each block being bolted to one pair of said bars, the bolts passing through slots in the bars, whereby adjustment of the blocks longitudinally of the bars is permitted, and a swinging dynamo supporting frame pivotally supported from said blocks, said frame having two parts extending downwardly from said blocks respectively, two parts extending laterally from each of said downwardly extending parts and two spaced apart cross members parallel with the car axle, connecting the laterally extending members on one side with the laterally extending members on the other side of the suspension, and means whereby the dynamo is carried by said cross members. 80 85 90

5. A dynamo suspension having in combination with a car truck, supporting means carried thereby, including a member having side arms and a cross piece, the side arms being pivotally supported at their upper ends, and having its lower portion bent laterally to one side, a second member having a cross piece parallel with the cross piece of the first member but spaced therefrom and side arms clamped to the first member where it is bent laterally, and means for supporting a dynamo on said cross pieces. 105 110

6. A dynamo suspension having in combination with a car truck supporting bars extending from said truck, a supporting frame pivotally suspended from said bars, said frame having two upright members pivotally supported at their tops and two cross pieces rigidly secured at their ends to said upright members, clamps for clamping one of said cross pieces to said upright members, said clamps having extending ears, tension means connected to said ears tending to swing the frame away from the truck and a dynamo supported on said cross pieces. 115 120 125

7. A dynamo suspension arrangement having, in combination, a supporting frame or swinging structure comprising a member having on each side a vertical portion piv- 130

oted to said frame, a portion at an angle to the vertical and a horizontal portion connecting said sides, and a second member connected to the lower end of the vertical 5 portions of the first member and at an angle to the vertical but opposite to the corresponding portion of the first member, said

second member also having a horizontal portion parallel to the corresponding portion of the first member, said horizontal portions being adapted to carry the dynamo. 10

In testimony whereof, I have signed name to this specification.

WILLIAM F. BOUCHE.
